UNITED STATES PATENT OFFICE.

ROLLIN H. BLACKLIDGE, OF ALHAMBRA, CALIFORNIA.

DESIGN FOR A LAMP-POST.

41,874.

Specification for Design.

Patented Oct. 31, 1911.

Application filed June 19, 1911. Serial No. 634,194. Term of patent 14 years.

To all whom it may concern:

Be it known that I, ROLLIN H. BLACKLIDGE, a citizen of the United States, residing at Alhambra, in the county of Los Angeles and State of California, have invented a new, original, and ornamental Design for a Lamp-Post, of which the following is a specification, reference being had to the accompanying drawing, forming a part thereof, which is a perspective view of my new lamp-post.

In the drawings I have shown my post provided with electric lights 5. The cap 6 is made of cast metal. The shaft 7 and base 8 are hollow and are made of concrete where

cheapness of construction is desired. The base is provided with recessed surfaces 9 and the ornamentations consisting of a bell 10, crescent 11 and star 12 are in bas-relief.

I claim:

The ornamental design for a lamp-post as shown and described.

In witness that I claim the foregoing I have hereunto subscribed my name this 7th day of June, 1911.

ROLLIN H. BLACKLIDGE.
